UNITED STATES PATENT OFFICE.

FRIEDRICH WIELAND, OF POUGHKEEPSIE, NEW YORK, ASSIGNOR TO THE ARLINGTON COMPANY, OF NEW YORK, N. Y., A CORPORATION OF NEW JERSEY.

MANUFACTURE OF COMBS.

1,092,883.

Specification of Letters Patent. Patented Apr. 14, 1914.

Application filed July 26, 1913. Serial No. 781,355.

To all whom it may concern:

Be it known that I, FRIEDRICH WIELAND, a citizen of the United States, resident of the city of Poughkeepsie, in the county of Dutchess and State of New York, have invented certain new and useful Improvements in the Manufacture of Combs, of which the following is a specification.

The invention relates to the manufacture 10 of combs.

In the carrying out of the present invention a piece of stock is preferably pressed between dies that are properly constructed and arranged to form a comb blank in 15 which all of the teeth are practically of the desired final size and shape and in which the superfluous stock that remains at the end of the die forming operating is preferably of substantial thickness between the teeth 20 and at the outer portions of the comb and is connected to the rest of the comb by thin frail webs that are easily broken or severed, whereby substantially all of the superfluous material or stock not required in the comb 25 and which is located between the teeth or elsewhere may be quickly and easily removed. A pair of dies adapted to accomplish this purpose may be provided with 30 matrices having teeth forming depressions therein. These teeth forming depressions are defined at their sides by projecting portions, and it will be noted that the corresponding projecting portions on opposing dies closely approach each other about mid- 35 way of the teeth of the comb when the latter is being pressed between the dies at or near the end of the pressing operation. One or both sets of the adjacent portions of these 40 projections are provided with cutting edges that extend along and adjacent to the teeth that have been formed in the grooves in the die. The projecting portions on at least one of the dies are preferably grooved between 45 the cutting edges so as to provide a receiving space whereby stock not required for the formation of the particular comb may be left with a substantial thickness. The cutting edges on one of the dies score or groove 50 the material along the teeth and coöperate with the opposing projecting portions on the companion die, which last mentioned portions may or may not be provided with grooved portions between cutting edges, and thus when a blank piece of stock, for instance of rectangular shape, is pressed be- 55

tween the dies, practically all of the stock not required for the formation of the particular comb will be left with substantial thickness and will adhere to the comb only by a thin fin or web.

The comb blank above referred to, dies that may be employed in the manufacture of said blank and a method of manufacturing combs by first forming such a comb blank and finally finishing the blank to form a 60 comb are fully described in the pending applications for United States Letters Patent, Serial Nos. 580,950 and 580,951, filed by myself on September 8th, 1910.

One object of the present invention is to 70 shape, by pressing between dies, a comb having the back thereof substantially thicker than the thickness of the stock from which the comb is formed.

The above and other objects of the invention will be more fully described hereinafter in the specification and will also be pointed out more fully in the following claim.

As showing certain embodiments of the invention reference is made to the drawings 80 forming a part of this specification and in which—

Figure 1 is a plan view of a supporting die for shaping a pair of combs arranged back to back. Fig. 2 is a partial side and 85 vertical sectional view taken on the line 2—2 looking in the direction of the arrows. In this view the upper die is shown in juxtaposition on the lower or supporting die. Fig. 3 is a vertical sectional view through the 90 comb back forming depression and a tooth forming depression in the die. This view is taken on the line 3—3 of Fig. 1. Fig. 4 is a vertical sectional view through the comb back forming depression and a depression 95 located between cutting or scoring edges in a projecting part between adjacent teeth forming depressions or matrices. This view is taken on the line 4—4 of Fig. 1. Fig. 5 is a perspective view of a piece of stock that 100 may be utilized in the production of combs by the dies illustrated in Figs. 1 to 4. Fig. 6 is a plan view of an end portion of a comb blank partially shaped and illustrates the appearance of the same when the dies have 105 been forced only partially together. Fig. 7 is a plan view showing the appearance of a comb blank when removed from the dies at the end of the pressing operation. Fig. 8 is a sectional view taken on the line 8—8 of 110

Fig. 7. Fig. 9 is a sectional view taken on the line 9—9 of Fig. 7. Fig. 10 is a plan view showing an end portion of the comb formed from the blank illustrated in Fig. 7 5 immediately after the removal of the superfluous stock which was of substantial thickness. Fig. 11 is a plan view of a portion of the superfluous stock such as was removed from the partially finished comb illustrated 10 in Fig. 10. Fig. 12 is a sectional view taken on the line 12—12 of Fig. 11. Fig. 13 is a transverse vertical sectional view of a modified form of die for use in the forming of comb blanks. Fig. 14 is a plan view of the supporting die shown in Fig. 15. Fig. 15 is a vertical 15 sectional view showing in cross section the dies arranged in juxtaposition with a piece of stock pressed therebetween. The projecting portions between the teeth forming matrices 20 in the upper die shown in Fig. 15 are provided with grooved portions between cutting or scoring edges that extend along the teeth, which cutting or scoring edges are located adjacent to the teeth and are on said projecting portions. This figure illustrates a 25 section taken on the line 15—15 of Fig. 14. Fig. 16 is a transverse sectional view through the tooth and back portion of a pair of combs in a comb blank such as is produced 30 in the dies illustrated in Figs. 14 and 15. This figure also shows in dotted lines the cross section of the piece of stock which was utilized to produce this comb blank. Fig. 17 35 is a plan view of a rectangular piece of stock which may be utilized in the production of combs in said dies. Fig. 18 is a view of an end portion of the finished comb; Fig. 19 is a sectional view taken on the line 19—19 of Fig. 18; Fig. 20 is a sectional view of a single tooth taken as on the line 20—20 of Fig. 19; Fig. 21 is a sectional view taken as on the line 21—21 of Fig. 19.

The reference character 1 designates a lower or supporting die which may be utilized 45 in the production of combs from celluloid or like substances when in a plastic condition. A coöperating die 2 is located above the lower or supporting die and is provided with suitable pins 3 that enter the holes 4 50 in the lower die to serve as a guiding means whereby the two dies will properly register when they are forced together by a hydraulic press or any other suitable pressing means. The upper and lower companion 55 dies are each provided with comb forming matrices which comprise longitudinally extending depressions 5 in which the back portions of the combs are formed, the large transversely extending depressions 6 at the 60 ends of the matrices in which the end teeth are formed and the intermediate transversely extending depressions 7 in which the intermediate teeth of the comb are formed.

From an inspection of Figs. 1 and 2 it will 65 be observed that each of the dies is provided

with projecting portions 8 that are located between the depressions 7 in which the intermediate teeth are formed. The projecting portions 8 on the opposing dies coöperate and oppose each other and each of said projections is provided with cutting or scoring edges 8^a between which are located the grooved portions 8^b which are clearly illustrated in Figs. 1, 2 and 4.

When a piece of stock such as celluloid in 70 plastic condition is pressed between comb forming dies having between the tooth forming depressions coöperating projecting portions which oppose each other and which approach each other about midway of the teeth of the combs, it is impossible to press the dies together a sufficient amount to force from between the dies all of the material not required in the particular comb.

In order that any superfluous material remaining after the pressing or shaping operation may be readily removed, the dies shown in Figs. 1, 2 and 4 have been provided on the projecting portions between the tooth forming depressions with cutting edges 8^a, 85 between which are located the grooved portions 8^b. Due to the grooved portions 8^b the superfluous material that is located between the teeth will be permitted to retain a substantial thickness. During the pressing 90 operation some of the superfluous material will be permitted to flow along the grooved portions 8^b as the dies are forced together. The cutting or scoring edges 8^a that are on the projections and that are located along 100 the comb teeth, cut or score the material so that the comparatively thick portion between the comb teeth will be connected while in the comb blank to said teeth only by a thin frail web. It will also be observed that 105 the dies terminate at practically the free ends of the comb teeth so that any excess material which is located along said free ends at the termination of the operation of pressing or shaping the comb blank will be extruded beyond the dies and will be connected to the rest of the comb by merely a thin web. The dies are also grooved at 9 to receive any excess material which is located 110 at the end portions of the comb blank.

It will be noted that either the lower or supporting die or the upper die or both the said dies may be provided with cutting edges, as indicated by reference character 115 9^a, whereby said superfluous material at the end of the comb blank will adhere to the comb merely by a thin frail web which extends along the outer portions of the end teeth of the comb.

A piece of celluloid stock suitable for use 120 in the manufacturing of combs by means of the dies illustrated in Figs. 1 to 4 is shown in Fig. 5 and is designated by the reference character 10 in said last mentioned figure. A comb blank which is made by pressing 130

said piece of celluloid stock between the dies illustrated in Figs. 1 to 4 is designated by the reference character 11 in Fig. 7. The superfluous stock which may extend along the free end of the teeth at the termination of the pressing operation is designated by the reference character 12, while 13 designates the superfluous stock at the end of the comb blank.

10 In Figs. 8 and 9 the superfluous stock between the teeth and which is of material thickness is designated by 14 and from a careful inspection of said Figs. 7 to 9 it will be apparent that all of the superfluous stock adheres to the finally shaped combs, that are arranged back to back, merely by the thin webs 12^a, 13^a and 14^a. Consequently all of this superfluous stock can be readily removed from the combs simply by applying sufficient pressure upon the portion of the stock desired to be removed to rupture the thin frail webs which connect said stock to the rest of the comb proper.

15 In Fig. 6 there is illustrated the way in which a comb blank may appear at an intermediate stage of the pressing operation. In other words, the dies have not been completely forced together and thus in this figure there is shown a comb only partially formed.

20 The superfluous stock may be removed all at once or in large pieces as illustrated in Fig. 11. In Fig. 12 it will be clearly seen that the superfluous portion of the material which has been removed from between the teeth of the comb is of substantial thickness.

25 The appearance of the comb immediately after the superfluous stock has been removed therefrom is illustrated in Fig. 10. In this figure it will be apparent that there are small portions 12^x, 13^x and 14^x of the thin webs which must be buffed off after the webs have been broken in the removal of the superfluous stock from the comb. Since 30 these portions of the webs which must be buffed off are comparatively small, it will be manifest that very little work is necessary in the operation of finishing the comb.

35 In Figs. 1, 3 and 4 it will be observed that each of the dies is provided with a longitudinally extending ridge 15 that separates the comb forming matrices on opposite sides thereof. The ridge 15 in the lower die is opposed by a similar ridge 15 in the upper die and the two together coöperate to force a certain portion of the material laterally into the comb forming matrices or recesses on opposite sides thereof. These ridges also closely approach each other, whereby only 40 a thin web will connect the combs which are arranged back to back in the blank. This web is designated by the reference character 15^a in Fig. 8.

45 In Fig. 13 the longitudinally extending ridge 16 is wider than ridge 15 illustrated

in the dies in Figs. 3 and 4 in order that more material may be forced laterally into the comb receiving matrices 17—17 on opposite sides thereof. This ridge 16 may be provided with the groove 18 which, to a material extent, can be designed to determine the amount of material that will be forced laterally into the matrices. For instance, by making the groove 18 very small a comparatively large amount of material will be forced laterally into the comb forming matrices, whereas if the groove 18 is made much larger a correspondingly less amount of material will consequently be forced laterally into said matrices.

50 In Figs. 14 and 15 dies are illustrated for forming the comb blank shown in cross section in Fig. 16, from which comb blank the comb illustrated more in detail in Figs. 18 to 20 is produced.

55 From an inspection of Figs. 14 and 15 it will be observed that the projecting portions 19 between the teeth forming depressions on the lower die 20 are not provided with grooves between scoring or cutting edges that are arranged adjacent to the teeth. The projecting portions 21 between the teeth forming depressions on the upper die, however, are provided with the grooved portions 21^b that are located between the cutting edges 21^a which are arranged along the teeth. The function of the cutting edges 21^a and the grooved portions 21^b, however, are practically the same as the function of the cutting edges 8^a and the grooved portions 8^b shown and described in connection with Figs. 1 and 2.

60 In Fig. 15 it will be observed that the superfluous stock 22 which is located between the teeth 23, and also the superfluous stock 24^x are both of substantial thickness. This stock is all connected to the rest of the comb only by thin frail webs as 23^x and 24^y that are readily broken.

65 A piece of stock which is utilized in the manufacture of the combs, shown in detail in Figs. 18 to 20, by means of the dies shown in Figs. 14 and 15, is designated in Figs. 16 and 17 by the reference character X. From the first mentioned figure it will be observed that the stock is of much less thickness than the thickness of the final comb and is also of less width than is the width of the comb blank at the end of the pressing operation. As a matter of fact, in the pressing of this particular piece of stock X between the dies illustrated in Figs. 14 and 15, the stock from which the comb blank is made is materially thickened during the pressing operation and is also spread laterally sufficient to form the comb blank illustrated in sections in Figs. 15 and 16, and which is designated X'. Similar remarks also apply to the comb blank illustrated in Figs. 7 to 9, and which is made from the 70 75 80 85 90 95 100 105 110 115 120 125 130

rectangular strip of stock 10 illustrated in Fig. 5. The piece of stock 10 is thinner than the comb backs, as will be noted from an inspection of Figs. 5 and 8.

5 From an inspection of Figs. 14 to 16, and also from what has preceded in the body of this specification, it will be noted that a pair of combs are formed back to back from a strip of stock which presents a surplus of material at the points between the backs of the combs and an insufficiency of material at the adjacent back forming portions, but that when the dies are pressed together so as to form the connected comb blanks shown in 10 Fig. 16, the superfluous material between the backs will be caused to flow toward and into the back forming portions of the comb to supply some material for said back portions.

The comb which is made from the blank 20 designated X' is illustrated in Fig. 18 and is designated by the reference character Y. In the comb blank the combs are arranged back to back. Subsequently they are broken apart and the superfluous stock is removed 25 by the severing of the frail webs. The combs are then finished as by buffing or in any other suitable manner.

Fig. 19 is a cross section taken on the line 19—19 of Fig. 18 and shows the true shape 30 and size of the back of the comb as defined by the dies 21 and 22.

Fig. 20 shows in cross section the shape of the intermediate teeth of the comb and is a view taken on the line 20—20 of Fig. 19.

35 The projecting portion between the teeth

of the dies 20 and 21 is rounded at 21^y so as to produce in the finished article the fillets Z shown in Fig. 21. Due to this construction it will be apparent that no sharp line exists between the back of the comb and the 40 place where the teeth merge into the back portion. Consequently there is little likelihood of the teeth being broken from the back of the comb at that point, as is the case with cut combs of the present day. 45

The improvements herein set forth are not limited to the precise construction and arrangement of parts shown and described, as they may be embodied in various forms and modifications without departing from the 50 spirit and scope of the invention.

What I claim is:

The process of forming combs back to back from a strip of stock having a surplus of material at the points between the backs 55 and an insufficiency of material at the adjacent back forming portions, said process consisting in placing said strip of stock between a pair of opposed dies and pressing said dies toward each other to cause the surplus material between the backs to flow toward and into the back forming portions to supply some material for the latter. 60

This specification signed and witnessed this 24th day of July, A. D. 1913.

FRIEDRICH WIELAND.
